H. L. HILL,
COMBINATION NECKTIE HOLDER AND COLLAR BUTTON.
APPLICATION FILED NOV. 3, 1920.

1,414,412.

Patented May 2, 1922.

INVENTOR,
Harry L. Hill
by E. M. Bond
ATTORNEY.

UNITED STATES PATENT OFFICE.

HARRY LIONEL HILL, OF BELLAMY, ONTARIO, CANADA.

COMBINATION NECKTIE HOLDER AND COLLAR BUTTON.

1,414,412.

Specification of Letters Patent.

Patented May 2, 1922.

Application filed November 3, 1920. Serial No. 421,591.

To all whom it may concern:

Be it known that I, HARRY L. HILL, a citizen of the Dominion of Canada, residing at Bellamy, in the county of Leeds and Province of Ontario, have invented certain new and useful Improvements in Combination Necktie Holders and Collar Buttons, of which the following is a specification.

The present invention relates to a combination cravat holder and collar button, and the principal object is to provide a device of the character described, which will securely hold the cravat in proper position upon the collar, and which is more particularly adapted for attachment to permanently knotted neckwear.

A further object of the invention is to provide a holder and its associate button element, which may be quickly secured together, and wherein the probability of the disconnection of the holder and tie from the collar is obviated.

With these and other objects in view, the invention consists in the construction, combination and arrangement of parts, as will be hereinafter fully described, illustrated in the accompanying drawings, and pointed out in the claims hereunto appended.

Figure 1 is a rear perspective view of a cravat, illustrating its attachment to the holder.

Fig. 2 is a perspective view of the same, taken at the side thereof.

Fig. 3 is a perspective view of a collar and tie, with the holder schematically illustrated.

Fig. 4 is a perspective view of the button fastening device for the holder, and illustrating the attachment of the same thereto; and

Fig. 5 is a magnified cross section of the holder or button element.

Referring to the drawings, like numerals designate like parts in the various drawings.

Generally speaking, necktie holders of the well-known and ordinary type are not in general public use, as the same, owing to their propensity for becoming unfastened from the collar, frequently cause great inconvenience and embarrassment.

With the object of overcoming this difficulty, I have provided a tie holder, which is formed in principle, of a single piece of wire, bent at approximately its medial point to form a coil 1, of preferably one convolution, and the extensions 2 and 3. The upper extension 2 is bent in arc form, and has its

free end terminating in a relatively sharp point 4. The lower extension 3 extends in the same arc form as the upper extension 2, and this lower extension, at approximately its medial part, is first bent downwardly at right angles to its longitudinal continuity to form the vertical portions 4' and 5, then the vertical portions 4' and 5, are in turn bent outwardly in horizontal plane to form the spear-shaped portion 6. The free end of the lower extension 3, is bent upwardly at 7 and over to form a catch 8, adapted for the reception of the pointed end 4 of the upper extension 2.

The tie is first knotted, and the upper extension 2 is passed through the upper folded part of the tie, and the latter is positioned centrally of the said extension.

For securing the holder in place, I provide a button or disk 9, and the said button at its central part is formed with spaced openings 10 and 11 and a relatively wide hollow extension member 12 is attached to the button, and the said extension is formed with a series of tongues 13, which pass into the openings 10 and 11 of the button. The tongues 13 are upset against the outer surface of the button, and serve to hold the said extension in position thereupon. The extension 12, by reason of its hollow construction, is adapted for the reception of the resilient spear portion 6 of the holding member, and the bowed wire portion engages the edge walls of the extension 12.

To release the holder from the button extension, and consequently the necktie and holder from the collar, it is only necessary to apply pressure of the thumb and forefinger upon the vertical portions 4' and 5 of the holder, thereby contracting said spear shaped loop portion 6 and resulting in the disconnection of the holder from the button.

The button 9 may be used in the manner similar to that of the ordinary collar button, namely the shank 12 is passed through button-hole of the shirt band in the usual manner.

By the arcuate configuration of the extensions 2 and 3 of the holder, the same will readily conform to the curvature of the collar and will thus be held between the folds thereof.

From the foregoing, it is thought that the construction of my invention will be clearly understood, and, therefore, a more extended explanation has been omitted.

Having thus described my invention, what I claim as new, and desire to secure by Letters Patent, is:

1. A necktie holder comprising in a single integral element a resilient member bent at substantially its medial point to form a coil with substantially parallel extensions therefrom, the upper extension being bent in arc form with its free end terminating in a substantially sharp point, the lower extension being extended in substantially the same arc form and at its medial point bent downwardly at right angles to the extension and thence bent at substantially right angles thereto to form a spear-shaped portion, the free end of the lower extension being bent upwardly to form a catch for co-operation with said sharp point, and means cooperating with said necktie holder for securing the same to a collar or neckband.
2. A necktie holder comprising in a single integral element a resilient member bent at substantially its medial point to form a coil with substantially parallel extensions therefrom, the upper extension be-

ing bent in arc form with its free end terminating in a substantially sharp point, the lower extension being extended in substantially the same arc form and at its medial point bent downwardly at right angles to the extension and thence bent at substantially right angles thereto to form a spear-shaped portion, the free end of the lower extension being bent upwardly to form a catch for co-operation with said sharp point, and a securing device for said holder comprising a disc having spaced openings, a relatively wide hollow extension attached to said disc and formed with a series of tongues which pass through openings in the disc and upset against the outer surface thereof, said extension being adapted to receive the spear portion of the holding member.

In testimony whereof I affix my signature in the presence of two witnesses.

HARRY LIONEL HILL.

Witnesses:

L. V. FITZPATRICK,
F. B. TABER.
